UNITED STATES PATENT OFFICE.

WILLIAM E. JOHN, OF DAYTON, OHIO, ASSIGNOR TO GENERAL MOTORS RESEARCH CORPORATION, OF DAYTON, OHIO, A CORPORATION OF DELAWARE.

PISTON.

Application filed April 15, 1922. Serial No. 553,106.

To all whom it may concern:

Be it known that I, WILLIAM E. JOHN, a citizen of the United States of America, residing at Dayton, county of Montgomery, 5 and State of Ohio, have invented certain new and useful Improvements in Pistons, of which the following is a full, clear, and exact description.

This invention relates to pistons for internal combustion engines and has particular reference to cooling means therefor.

As is well known, a great problem in piston design is the provision of means to keep the piston cool enough to guarantee 15 the proper operation thereof when the engine is working hard. Some of the difficulties encountered are the excessive expansion of the piston making it necessary to provide more clearance between the piston 20 and cylinder walls; the excessive heating up of the central part of the top of the piston thereby reducing the compression which can be safely used without preignition and reducing the volumetric efficiency of the engine cylinder, and the difficulties of properly lubricating the piston. Also the high 25 temperature of the central part of the top of the piston necessitates a greater thickness for strength considerations and therefore adds to the weight of the piston which 30 for balance considerations should be as light as possible.

Among the objects of the present invention is to enable a considerable decrease in 35 weight of cast iron pistons, at the same time providing for a heat conducting capacity equal to or greater than that of thick sections commonly used.

In the drawing:

40 Fig. 1 is a vertical section through the piston.

Fig. 2 is a view of the metal insert of high 45 heat conductivity which is cast in the piston, the left half of the insert being shown in section.

Fig. 3 is a plan view of the metal insert.

Similar reference characters refer to similar parts throughout the several views.

Numeral 10 designates the metal insert, 50 which is preferably made of sheet copper and of substantially the same dimensions as the piston which is to be cast around it. The upper part of the insert which falls opposite the piston ring grooves is of 55 reduced diameter, as shown, for obvious

reasons. This insert 10 is set in the mold and the piston 15 cast about it in a manner which will be readily understood by those skilled in the art. Preferably the insert 10 is provided with a plurality of small holes 60 11 having the metal turned in or out to form short flanges 12 around the holes. These flanges 12 aid in carrying the heat to the inner surface of the piston where the heat is dissipated to the air and oil in the 65 crank case of the engine. The top of the piston may also have similar flanges 13 extending upwardly, as shown, to aid in conducting the heat from the upper surface of the piston down to the copper insert. The 70 flanges 12 and 13 preferably extend to the surface of the cast metal, but if desired they may extend only to a point just below the surface of the cast metal.

The piston is preferably cast of cast iron 75 on account of its coefficient of expansion being the same as that of the cylinder walls and because of its satisfactory bearing qualities, but of course the scope of the invention includes the use of other cast metals 80 being used. The copper insert 10 greatly increases the heat conductivity over a similar piston without the insert and hence the piston will run much cooler and all the attending advantages obtained. If desired, 85 the copper insert may not extend the full length of the piston skirt, since the lower part of the skirt does not reach such high temperatures as the upper part and the heat conductivity of the cast iron alone may be 90 sufficient to properly cool the lower portions. In some cases it may be desirable to use the copper insert only in the top of the piston to aid in conducting the heat from the central portion which has the greatest 95 tendency to heat to the side walls of the piston. Of course in any of the above described modifications any metal of high heat conductivity may be used for the inserts instead of copper.

100 While the form of mechanism herein shown and described, constitutes a preferred form of embodiment of the present invention, it is to be understood that other forms might be adopted, all coming within the 105 scope of the claims which follow.

What I claim is as follows:

1. A cast metal piston having embedded within its head a continuous insert of metal 110 extending throughout said head and of

higher heat conductivity than said cast metal.

2. A cast metal piston having cast within its walls an insert of metal of higher heat conductivity than said cast metal, said insert having portions extending to the surface of the piston walls.
5. A cast metal piston having embedded within its head and skirt portions a continuous sheet metal insert of higher heat conductivity than said cast metal.
10. A cast metal piston having cast within

its walls a sheet metal insert of higher heat conductivity than said cast metal, said insert having portions extending to the surface of said cast metal.

15. A cast metal piston having cast within its walls a continuous sheet metal cup-shaped insert of the general form of the piston and having higher heat conductivity than said cast metal.

20. In testimony whereof I hereto affix my signature.

WILLIAM E. JOHN.
